FUR PELT OR SKIN STRETCHING APPARATUS

Carl H. Donner, Summit, N. J., assignor to The Chapal Donner Corporation, Newark, N. J., a corporation of New Jersey

Application July 1, 1946, Serial No. 680,598

16 Claims. (Cl. 69—24)

1

This invention relates to apparatus for use in the preparation of fur employed in the manufacture of felt hats or in the production of other felt products; and the invention has reference, more particularly, to mechanism for stretching and smoothing fur pelts or skins preparatory to cutting away the fur or hair therefrom.

The fur of rabbits, hares, nutria, muskrat, beaver and similar animals is largely used as a fur for felting, and especially for the felting of hat bodies. Quantities of the fur pelts or skins of these animals are ordinarily packed in more or less compressed bundles or bales for shipment from the source of supply thereof to fur processors. The fur processors prepare the fur by carotting, dyeing and like treatments, and thereupon cut the fur from the skin, thereby making the same ready for use by the manufacturer of felt hats or other felt products.

Fur pelts or skins, when baled for shipment to the processor, become more or less wrinkled and otherwise distorted in the packing, and tend to dry out and set or more or less stiffen in such condition. Due to such wrinkling or like distortion, when a pelt or skin is subjected to a cutting machine for removal of the fur from the skin, the cutting knives either fail to reach the bases of the hairs so as to cut them off close to the skin, or the knives cut off shreds of skin with the fur without severing the hair therefrom; either of which occurrence results in considerable loss of valuable fur. Such occurrences can be substantially avoided, or at least considerably limited, if the wrinkles or like distortions of the skin are removed and smoothed out, so as to leave the skin stretched into substantially flat and smooth condition; in which condition the cutting machine knives can best reach into and sever the hairs at points very close to the skin surface, and with minimum risk of chipping the skin.

Having the above stated conditions in view, it is an object of this invention to provide a novel and efficient apparatus for stretching and smoothing fur pelts or skins.

The invention has for another object to provide a fur pelt or skin stretching and smoothing apparatus which is quick acting and efficient. To this end the apparatus comprises means to first stretch the skin to remove wrinkles or like distortions therefrom while at the same time breaking down the stiffness thereof, and means to thereafter smooth or iron out the skin from a medial portion thereof outwardly and simultaneously in opposite directions, so as to effect an

2

equalized and uniformly applied final stretching and smoothing action thereupon without risk of tearing or otherwise injuring the skin or fur; means being provided for automatically passing the skin from the initial stretching means to the smoothing and ironing means, and thence for discharge from the apparatus.

Other objects of this invention, not at this time more particularly enumerated, will be understood from the following detailed description of the same.

An illustrative embodiment of apparatus according to this invention is shown in the accompanying drawings, in which:

15 Fig. 1 is a side elevation of the apparatus; Fig. 2 is a fragmentary transverse vertical section therethrough, taken on line 2—2 in Fig. 1; Fig. 3 is another transverse vertical section therethrough, taken on line 3—3 in Fig. 1; and Fig. 4 is a schematic central longitudinal vertical sectional view of the apparatus.

Fig. 5 is an enlarged longitudinal sectional view of the smoothing and ironing roll of the apparatus, with parts thereof shown in elevation; 25 Fig. 6 is a cross-sectional view, taken on line 6—6 in Fig. 5; Fig. 7 is a cross-sectional view, taken on line 7—7 in Fig. 5; and Fig. 8 is another cross-sectional view, taken on line 8—8 in Fig. 5.

Similar characters of reference are employed in 30 the above described views to indicate corresponding parts.

Referring to said drawings, the reference character 10 indicates a suitable framework for supporting the operative parts of the apparatus; 35 said framework including side members 11.

Located at the receiving end of the apparatus are a pair of transverse stretcher rolls by means of which the initial skin stretching treatment is effected, the same comprising a lower stretcher

40 roll 12 and a cooperating upper stretcher roll 13. The shaft 14 of the lower stretcher roll 12 is journaled in and between stationary bearings 15 which are supported by the side members 11 of the framework. The shaft 16 of the upper 45 stretcher roll 13 is journaled in and between vertically adjustable bearings 17 which are also supported by the side members 11 of the framework.

The lower stretcher roll 12 is provided with a plurality of axially spaced annular stretcher 50 flanges 18, and the upper stretcher roll 13 is provided with a plurality of like axially spaced annular stretcher flanges 19, so located however as to be disposed in staggered relation to those of said lower stretcher roll. Said stretcher rolls 12 and 13, as operatively related, are spaced apart a

suitable distance, and so that the peripheries of the stretcher flanges 18 of the one dovetail between or lap the stretcher flanges 19 of the other, but in spaced relation to each other and to the roll body peripheries so as to leave intervening space for the reception and passage of a fur pelt or skin therebetween. The roll shafts 14 and 16 are provided with intermeshing gears 20 and 21, whereby rotary movement of the lower stretcher roll 12 is transmitted to the upper stretcher roll 13.

Means is provided for adjusting the relative spacing of the stretcher rolls 12 and 13. An illustrative form of such means, as shown, comprises a transverse bridge plate 22 which is affixed to and between the side members 11 of the framework above said rolls. Supported in connection with the respective ends of said bridge plate 22, so as to be disposed in axially aligned relation to and above the adjustable bearings 17, are fixed bearings 23 in which are journaled vertical adjusting shafts 24, the screw-threaded lower end portions of which are threaded into said adjustable bearings 17. Fixed on said adjusting shafts 24, above the bridge plate 22, are bevel gears 25. Supported by upwardly yieldable bearings 26, which are mounted on the bridge plate 22, is a transmission shaft 27, to the ends of which are fixed bevel gears 28 to respectively mesh with the bevel gears 25 of said adjusting shafts 24. One of said adjusting shafts 24 is provided with an upward extension 29, upon the end of which a hand wheel 30 is affixed.

To adjust the spacing of the upper stretcher roll 13 relative to the lower stretcher roll 12, the hand wheel 30 is turned to rotate the adjusting shaft 24 with which it is connected. The movement of the one thus rotated adjusting shaft 24 is transmitted to the other adjusting shaft, in corresponding direction and degree, by the transmission shaft 27 and associated gearing, whereby the simultaneous turning of said adjusting shafts 24 will cause their screw-threaded portions to uniformly and equally raise or lower, as the case may be, the adjustable bearings 17 by which the ends of the upper stretcher roll 13 are journaled, thus adjustably positioning the latter relative to the lower stretcher roll 12 in desired parallel spaced relation thereto. It will be noted that the transmission shaft 27 is supported by the bearings 26 which are upwardly yieldable against the tension of compression springs 31 cooperative therewith, whereby, since the adjusting shafts 24 may slide in the bearings 23, the arrangement yieldably supports the upper stretcher roll 13 for separative movement relative to the lower stretcher roll 12. This is very desirable, since it not infrequently happens that a fur pelt or skin, passed between the stretcher rolls, possesses a hardened lump, knot or other excrescence, which, unless the stretcher rolls are permitted to yield thereto and separate to permit passage thereof therebetween, may cause jamming of said rolls or injury to their stretcher flanges 18-19.

Suitably supported in connection with the forward end of the framework, for extension toward the nip of the stretcher rolls 12-13, is a feed-table 32. Journaled in and across the framework side members and in spaced relation to and above the inner end of the table surface, is a driven feed roller 33. Said feed roller 33 is driven from the upper stretcher roll 13 by gearing comprising a drive gear 34 which is affixed to the shaft 16 of said upper stretcher roll, a suitably supported idler gear 35, and a driven gear 36 with

which said feed roller is provided. A fur pelt or skin to be treated is laid, fur side down, upon the feed-table 32, and is then pushed forward thereon until its leading end is engaged by the feed roller, whereupon the latter advances the same whereby to pass it into the nip of said stretcher rolls 12-13.

As the fur pelt or skin passes between the stretcher rolls 12-13 it will be engaged by the 10 stretcher flanges 18 and 19 thereof. Those portions of the skin contacted by the stretcher flanges 18 of the lower stretcher roll 12 will be pushed upwardly intermediate portions thereof which are snubbed over the adjacent laterally offset stretcher flanges 19 of the upper stretcher roll 13, while those portions of the skin contacted by the stretcher flanges 19 of the upper stretcher roll 13 will be pushed downwardly intermediate portions thereof which are snubbed over the adjacent laterally offset stretcher flanges 18 of said lower stretcher roll 12. The effect of this is to stretch the skin and thereby to stress the wrinkled, bulged or distorted parts thereof, whereby to pull or straighten out and thus remove said wrinkles, bulges and like distortions therefrom, while at the same time flexing the skin sufficiently to break down any set and stiffness thereof, so that the skin as a whole becomes desirably flexible, and therefore 20 adapted to be more efficiently handled and applied to dehauling mechanism. Cooperative with each stretcher roll is a doctor blade means 37 (see Fig. 4), which assures stripping of the fur pelt or skin from these rolls as it emerges therefrom.

Beyond the stretching rolls 12 and 13, so as to be supported by the framework and preferably located in a lower plane than that of the nip of said stretcher rolls, is a skin ironing and smoothing means or roll which is adapted to further 30 stretch and flatly iron out the preliminarily stretched skin and thus complete the stretching treatment thereof. This means comprises a non-rotatable transverse shaft 38, which is fixed in and between supporting bearings 39 with which the framework is provided. Fixed on said shaft is a cam cylinder 40. Rotatable on and about said cam cylinder 40 is a carrier cylinder or roll 41 upon which are mounted two sets of longitudinally reciprocable ironer members. One set of ironer members comprises a plurality of independently reciprocable ironer members 42 which are arranged side by side around the periphery of the roll 41, and so as to extend longitudinally from the medial portion of said roll toward one end thereof. The other set of ironer members comprises a plurality of like independently reciprocable ironer members 43 which are also arranged side by side around the periphery of the roll 41, but so as to extend longitudinally from the medial portion of the latter toward the opposite end thereof. The outer surfaces of said ironer members 42 are provided with transverse serrations or blunt teeth 44 which are directed toward that end of the roll 41 toward which said ironer members 42 extend. In like manner, the ironer members 43 are also provided with transverse serrations or blunt teeth 45 which are directed toward the opposite end of the roll 41 toward which said ironer members 43 extend.

Said ironer members 42 and 43 are each keyed to the carrier roll 41 so as to both revolve therewith and so as to be subject to guided longitudinal reciprocable movements thereon. To this end, headed coupling and guiding studs 46 are affixed to the carrier roll 41 for radial extension

therefrom, the heads of which are embraced and are slidably engaged by stepped guide slots 47 with which the under side of end portions of the ironer members are provided. Said cam cylinder 40 is provided, adjacent one end thereof, with a suitably shaped and obliquely pitched cam race 48 for cooperation with the one set of ironer members 42, and, adjacent its opposite end, with a correspondingly shaped but oppositely pitched oblique cam race 49 for cooperation with the other set of ironer members 43.

Affixed to the underside of each ironer member is a driver stud 50 which terminates in an anti-friction roller 51 adapted to engage and ride in an adjacent cam race of the cam cylinder. Said carrier roll 41 is provided, beneath each ironer member, with a longitudinal slotway 52 in which the driver stud of the driver member rides back and forth during the reciprocable movements of the same. The studs and rollers 50-51 of the set of ironer members 42 engage in the cam race 48 so as to be moved thereby and thus effect longitudinal reciprocable movements of the ironer members of said set back and forth between the medial portion and one end of the carrier roll 41. The studs and rollers 50-51 of the other set of ironer members 43 engage in the cam race 49 so as to be moved thereby and thus effect similar longitudinal reciprocable movements of the ironer members of said latter set thereof back and forth between the medial portion and the opposite end of said carrier roll 41.

Means is provided for delivering a skin discharged from the stretcher rolls 12-13 to and for operative engagement by the skin ironing and smoothing means or roll, and thence for discharge from the apparatus. Said means comprises an endless carrier apron 53 which is of a width substantially corresponding to the lengths of the stretcher rolls and the ironing and smoothing roll. The receiving end of said carrier apron 53 is supported by a transverse pulley roll 54, the shaft 55 of which is journaled in and between bearings 56 which are mounted on the side members 11 of the framework adjacent to the discharge side of the stretcher rolls 12-13, and in a plane above that of said ironing and smoothing roll. The discharge end of said carrier apron 53 is likewise supported by a similar transverse pulley roll 57, the shaft 58 of which is journaled in and between bearings 59 which are mounted on the framework side members 11 adjacent to the rearward end of the apparatus, and also in a plane above that of said ironing and smoothing roll. As thus mounted, the operative course of said carrier apron 53 descends from the stretcher rolls 12-13 to pass beneath the underside of the ironing and smoothing roll, thence ascending to the point of discharge at the rearward end of the apparatus. The return course of said carrier apron 53 passes over a vertically adjustable transverse tightener pulley roll 60, the shaft 61 of which is journaled in and between vertically adjustable bearings 62 which are suitably supported in connection with the framework, below the ironing and smoothing roll. It will be obvious that by vertically adjusting the tightener pulley roll 60, the tension of the carrier apron 53, as to its bearing against the underside of the ironing and smoothing roll, may be suitably regulated.

Mounted to run parallel to and for cooperation with the descending portion of the operative course of said carrier apron 53 is an endless conveyer belt 63 of corresponding width. The

lower end of said conveyer belt 63 terminates adjacent to the receiving side of the ironing and smoothing roll, and is supported by a pulley roll 64, the shaft 65 of which is journaled in and between bearings 66 which are affixed to the framework side members 11. The upper end of said conveyer belt 63 is located adjacent to the discharge side of the stretcher rolls 12-13, and is also supported by a pulley roll 67, the shaft 68 of which is journaled in and between adjustable bearings 69, adjustment of which governs the operating tension of said conveyer belt 63. In like manner, mounted to run parallel to and for cooperation with the ascending portion of the operative course of said carrier apron 53 is an endless conveyer belt 70 of corresponding width. The lower end of said conveyer belt 70 terminates adjacent to the discharge side of the ironing and smoothing roll, and is supported by a pulley roll 71, the shaft 72 of which is journaled in and between bearings 73 which are affixed to the framework side members 11. The upper end of said conveyer belt 70 is located adjacent to the discharge end of the carrier apron 53, and is also supported by a pulley roll 74, the shaft 75 of which is journaled in and between adjustable bearings 76, adjustment of which governs the operative tension of said conveyer belt 70.

Supported by and between the framework side members 11, to extend outwardly from the discharge end of the carrier apron 53 is a downwardly inclined discharge chute 77 for discharging the treated skins from the apparatus.

Suitably designed power transmission means is provided for operating the stretcher rolls, the ironing and smoothing roll and its cooperating carrier apron, and the conveyer belts associated with the latter. An illustrative form of such

power transmission means, as shown, comprises a power shaft 78 which is journaled in and between bearings 79 which are suitably located and supported in the lower part of the framework 10. Power may be applied to said power shaft 78

in any suitable manner, as e. g. by means of a driving pulley 80 affixed thereto. Affixed on and rotated by said power shaft 78 is a drive gear 81. Connected with the framework 10, respectively at opposite sides of said drive shaft 78,

are bearing brackets 82 and 83. Rotatively supported by the bearing bracket 82 is a driven gear 84 with which the drive gear 81 meshes in driving relation thereto. Driven by said gear 84 is a sprocket and chain transmission 85 adapted to

drive the lower stretcher roll 12 and through it the upper stretcher roll 13. Extending between the power shaft 78 and the carrier roll 41 of the ironing and smoothing means is a chain and sprocket transmission 86 adapted to operatively

rotate said carrier roll; the latter having a hub portion 87 and hollow shaft extension 88 upon which the driven sprocket 89 of said transmission 86 is affixed (see Fig. 5). Rotatively supported by the bearing bracket 83 is a driven gear

90 with which the drive gear 81 also meshes in driving relation thereto. Driven by said gear 90 is a sprocket and chain transmission 81 adapted to drive the pulley roll 57 and through it the carrier apron 53.

Means is also provided for driving the respective conveyer belts 63 and 70. This means, as shown, comprises a drive gear 92 which is fixed on the hollow shaft extension 88 of the carrier roll 41 of the ironing and smoothing means, whereby to be driven thereby. Said drive gear

92 drives the conveyer belt 63 through gearing 93 which is adapted to rotate the pulley roll 64. In like manner, said drive gear 92 also drives the conveyer belt 70 through gearing 94 which is adapted to rotate the pulley 71.

Upon issuing from the stretcher rolls 12-13, which perform the initial stretching of the fur pelt or skin as above described, the fur pelt or skin passes onto the descending portion of the operative course of the carrier apron 53, whereby to be engaged between the same and the overlying conveyer belt 63, thus being carried down to and for engagement with the ironing and smoothing roll. Since the apron 53 passes beneath the underside of the ironing and smoothing roll, the skin side or face of the fur pelt or skin is brought thereby into engagement with and firmly pressed against the reciprocated ironer members 42 and 43 which are carried by the rotated carrier cylinder or roll 41, while being advanced therewith by the movement of said carrier apron 53. The cam races 48 and 49 are so shaped that those portions thereof, which extend across the underside of the stationary cam cylinder 40, respectively incline from a point toward the medial portion of the latter outwardly toward the respective ends thereof, while those portions of said cam races, which extend across the upper side of said stationary cam cylinder, are oppositely inclined. As a result of this, when the studs and rollers 50-51 of the respective sets of ironer members 42 and 43 are caused to traverse the underside of the cam cylinder and the respective cam races 48-49 by the rotation of the carrier cylinder or roll 41, the ironer members 42, while engaged with the skin, are being moved longitudinally outward from the medial portion of the ironing and smoothing roll toward one end thereof, viz. the left hand end as shown, whereas the ironer members 43, while likewise engaged with the skin, are being simultaneously moved longitudinally outward from the medial portion of the ironing and smoothing roll toward the opposite end thereof, viz. the right hand end as shown. By reason of such operation of the ironer members 42-43, the same exert additional stretching and smoothing effect upon the skin, simultaneously in opposite directions leading from its medial portion, so as to exert equalized and uniformly applied pulling and smoothing action thereupon without risk of tearing or otherwise injuring the same, whereby any wrinkles or distortions thereof are quickly and finally ironed out, leaving the skin substantially smooth, flat and flexible. When, under rotation of the carrier cylinder or roll 41, the ironer members 42-43 pass beyond their skin engaging positions, the studs and rollers 50-51 thereof will traverse the inwardly inclined portions of the cam races 48-49, so as to be moved longitudinally inward and back to initial starting points toward the medial portion of the ironing and smoothing roll, and thus disposed to repeat their ironing and smoothing strokes upon any skin passed beneath and in contact therewith.

As the skin passes beyond the ironing and smoothing roll, it is moved outwardly by the ascending portion of the carrier apron 53, whereby to be engaged between the same and the overlying carrier belt 70, being thus carried to the outer ends of these parts, whereby to be discharged therefrom and onto the discharge chute 71, for descent along the latter and out of the apparatus.

Since various changes could be made in the

apparatus above described and as shown in the accompanying drawings without departing from the scope of this invention as defined in the following claims, it is intended that all matter contained in the foregoing description or shown in the accompanying drawing shall be interpreted as illustrative and not in a limiting sense.

I claim:

1. In apparatus of the kind described, a pair of rotated initial stretcher rolls each having axially spaced annular stretcher flanges projecting from their peripheries, the stretcher flanges of one said roll being in staggered and intervening relation to those of the other roll, a rotated ironing and smoothing means having longitudinally reciprocated ironer members mounted around the periphery thereof, and a driven carrier means adapted to receive work discharged from said initial stretcher rolls and to carry the same into operative engagement with said ironing and smoothing means and thence for discharge from the apparatus.

2. In apparatus of the kind described, a pair of rotated initial stretcher rolls each having axially spaced annular stretcher flanges projecting from their peripheries, the stretcher flanges of one said roll being in staggered and intervening relation to those of the other roll, a rotated ironing and smoothing means having longitudinally reciprocated ironer members mounted around the periphery thereof, said ironer members comprising two sets thereof respectively and simultaneously reciprocated in opposite directions between medial and the respective end portions of said ironing and smoothing means, and a driven carrier means adapted to receive work discharged from said initial stretcher rolls and to carry the same into operative engagement with said ironing and smoothing means and thence for discharge from the apparatus.

3. In apparatus of the kind described as defined in claim 1 including adjusting means for positioning said initial stretcher rolls in selected spaced apart relation one to the other, and means to support one of said rolls subject to yielding separative movement relative to the other thereof.

4. In apparatus of the kind described as defined in claim 2 including adjusting means for positioning said initial stretcher rolls in selected spaced apart relation one to the other, and means to support one of said rolls subject to yielding separative movement relative to the other thereof.

5. Apparatus for the purposes set forth comprising a pair of rotated initial stretcher rolls each having axially spaced annular stretcher flanges projecting from their peripheries, the stretcher flanges of one said roll being in staggered and intervening relation to those of the other roll, a feed table leading to said stretcher rolls, a rotated feed roller cooperative with the discharge end of said table and adapted to advance the work to and for engagement by said

6. stretcher rolls, a rotated ironing and smoothing means having longitudinally reciprocated ironer members mounted around the periphery thereof, said ironer members comprising two sets thereof respectively and simultaneously reciprocated in opposite directions between medial and the respective end portions of said ironing and smoothing means, and a driven carrier means adapted to receive work discharged from said initial stretcher rolls and to carry the same into engagement with said ironing and smoothing means at

a point whereby the work will be operatively contacted by ironer members of the respective sets thereof while said ironer members are moving in opposite outward directions, said carrier means being adapted to thence discharge the work from the apparatus.

6. In apparatus for the purposes set forth, an initial stretching means comprising a pair of rotated stretcher rolls each having axially spaced annular stretcher flanges projecting from their peripheries, the stretcher flanges of one said roll being in staggered and intervening relation to those of the other roll, a feed table leading to said stretcher rolls, a rotated feed roller cooperative with the discharge end of said feed table and adapted to advance the work to and for engagement by said stretcher rolls, adjusting means for positioning said stretcher rolls in selected spaced apart relation one to the other, and means to support one of said rolls subject to yielding separative movement relative to the other thereof.

7. In apparatus for the purposes set forth as defined in claim 5 including adjusting means for positioning said initial stretcher rolls in selected spaced apart relation one to the other, and means to support one of said rolls subject to yielding separative movement relative to the other thereof.

8. In apparatus of the kind described as defined in claim 2 wherein said ironer members are provided on their outer surfaces with transverse serrations directed toward their outer ends.

9. In apparatus of the kind described as defined in claim 5 wherein said ironer members are provided on their outer surfaces with transverse serrations directed toward their outer ends.

10. Apparatus for the purposes set forth comprising a pair of rotated stretcher rolls each having axially spaced annular stretcher flanges projecting from their peripheries, the stretcher flanges of one said roll being in staggered and intervening relation to those of the other roll, a rotated ironing and smoothing means having longitudinally reciprocated ironer members mounted around the periphery thereof, said ironer members comprising two sets thereof respectively and simultaneously reciprocated in opposite directions between medial and the respective end portions of said ironing and smoothing means, said ironing and smoothing means being located in a plane below that of the nip of said stretcher rolls, a driven endless carrier apron having its operative course arranged to provide a descending portion extending from a point adjacent to the discharge side of said stretcher rolls to pass around the underside of said ironing and smoothing means and an ascending portion extending from the latter to the discharge end of the apparatus, a driven endless conveyer belt cooperative with said descending portion of said carrier apron, and a second endless conveyer belt cooperative with said ascending portion of said carrier apron.

11. Apparatus for the purposes set forth as defined in claim 10 including a feed table leading to said stretcher rolls, and a rotated feed roller cooperative with the discharge end of said table and adapted to advance the work to and for engagement by said stretcher rolls.

12. Apparatus for the purposes set forth as defined in claim 10 including adjusting means for positioning said initial stretcher rolls in selected spaced apart relation one to the other, and means to support one of said rolls subject to yielding separative movement relative to the other thereof.

13. In apparatus of the kind described, an ironing and smoothing means comprising a non-

5 rotatable cam cylinder, a carrier roll adapted to be rotated about said cam cylinder, longitudinally reciprocable ironer members having serrated outer faces mounted on and around the periphery of said carrier roll, said ironer members comprising two sets thereof adapted to be simultaneously reciprocated in opposite directions between medial and the respective end portions of said carrier roll, said cam cylinder having a cam race for each set 10 of ironer members, the ironer members of each set thereof having activating means operatively engaged by the respective cam races, and a driven endless carrier apron adapted to operatively engage the work with outwardly moving ironer members of the sets thereof.

14. Apparatus for the purposes set forth comprising a pair of rotated stretcher rolls each having axially spaced annular stretcher flanges projecting from their peripheries, the stretcher flanges of one said roll being in staggered and intervening relation to those of the other roll, an ironing and smoothing means located in a plane below that of the nip of said stretcher rolls, said ironing and smoothing means comprising a 20 non-rotatable cam cylinder, a carrier roll adapted to be rotated about said cam cylinder, longitudinally reciprocable ironer members having serrated outer faces mounted on and around the periphery of said carrier roll, said ironer members 25 comprising two sets thereof adapted to be simultaneously reciprocated in opposite directions between medial and respective end portions of said carrier roll, said cam cylinder having a cam race for each set of ironer members, the ironer members 30 comprising two sets thereof adapted to be simultaneously reciprocated in opposite directions between medial and respective end portions of said carrier roll, said cam cylinder having a cam race for each set of ironer members, the ironer members 35 comprising two sets thereof having actuating means operatively engaged by the respective cam races, a driven endless carrier apron having its operative course arranged to provide a descending portion extending from a point adjacent to the 40 discharge side of said stretcher rolls to pass around the underside of said ironing and smoothing means and an ascending portion extending from the latter to the discharge end of the apparatus whereby to engage the work with outwardly moving ironer members of the sets thereof, a driven endless conveyer belt cooperative with said descending portion of said carrier apron, and a second endless conveyer belt cooperative with said ascending portion of said carrier apron.

15. In apparatus of the kind described as defined in claim 14 including a feed table leading to said stretcher rolls, and a rotated feed roller cooperative with the discharge end of said table and adapted to advance the work to and for engagement by said stretcher rolls.

16. Apparatus for the purposes set forth as defined in claim 14 including adjusting means for positioning said initial stretcher rolls in selected spaced apart relation one to the other, and means to support one of said rolls subject to yielding separative movement relative to the other thereof.
